UNITED STATES PATENT OFFICE.

HARRY J. MARTIN, OF PORTLAND, OREGON, ASSIGNOR OF ONE-HALF TO GUNDER T. TROMMALD, OF PORTLAND, OREGON.

SUSPENSORY BANDAGE.

1,164,950.

Specification of Letters Patent. Patented Dec. 21, 1915.

Application filed June 28, 1915. Serial No. 36,806.

To all whom it may concern:

Be it known that I, HARRY J. MARTIN, a citizen of the United States, residing at Portland, in the county of Multnomah and 5 State of Oregon, have invented a new and useful Suspensory Bandage, of which the following is a specification.

The device forming the subject matter of this application is a suspensory bandage and 10 the invention aims primarily to improve the construction of the testicle-sack.

In the present embodiment of the invention, the testicle-sack is fashioned from a flat strip of textile material, the construction 15 being such that the sack may be removed easily and be washed, or be replaced by another unsoiled testicle-sack.

It is within the scope of the invention to provide novel means for assembling the testicle-sack with the supporting means, and 20 to provide novel means for Shirring the normally flat strip into sack-like form.

It is within the province of the disclosure to improve generally and to enhance the 25 utility of devices of that type to which the present invention appertains.

With the above and other objects in view which will appear as the description proceeds, the invention resides in the combination 30 and arrangement of parts and in the details of construction hereinafter described and claimed, it being understood that changes in the precise embodiment of the invention herein disclosed can be made within 35 the scope of what is claimed without departing from the spirit of the invention.

In the accompanying drawings:—Figure 1 shows the invention in perspective; Fig. 2 is a plan of the strip from which the 40 testicle-sack is formed; Fig. 3 is a side elevation of the testicle-sack detached from the supporting means.

In carrying out the present invention there is provided a supporting means of any 45 desired sort, the same preferably being in the form of a belt 1 in which a buckle 2 may be interposed.

The testicle-sack is denoted generally by 50 the numeral 3 and is fashioned from a flat strip of textile material, the strip being denoted generally by the numeral 4. Opposed, parallel edges of the strip 4 may be hemmed as shown at 5. The ends of the strip 4 from which the testicle-sack is made are turned over upon themselves and stitched down as

shown at 6 to form tubular guides 7, the guides 7 being convexed in opposite directions, as shown at 8.

Assembled with the ends of the testicle-sack 3 are shirring means preferably in the 60 form of strings or ribbons 9, the ribbons 9 being passed through the tubular guides 7. Intermediate the ends of the guides 7, the ribbons 9 are secured thereto in any suitable manner as by stitching as shown at 10. 65 When the structure is in operative condition as shown in Fig. 1, the shirring ribbons 9 are of loop-shape and at their upper ends, eyes 11 are formed. Through the eyes 11 are passed suspension straps 12. The sus- 70 pension straps 12 are of loop-shape, one end of each strap 12, indicated at 14, being secured to the supporting belt 1 and the other end 15 of the suspension strap being upheld by means of a buckle 16. 75

Owing to the fact that the strip 4 out of which the testicle-sack 3 is formed is normally flat, the same may be detached readily and washed as easily as a handkerchief. Since the ribbons 9 are attached to the testicle-sack 3 intermediate the ends of the 80 guides 7, the testicle-sack will shir up evenly and symmetrically in the sack-like form shown in Figs. 1 and 3 and will not shift or alter its position longitudinally of the 85 ribbons 9. Since the guides 7 are outwardly convexed, away from each other, the testicle-sack will shape itself properly and will be given a slight intermediate sag as shown at 17, when in use. 90

From the foregoing it will be observed that in this application there is disclosed a suspensory bandage, the testicle-sack of which may readily be removed and laundered without difficulty. 95

Having thus described the invention, what is claimed is:—

1. A suspensory combining with a supporting means, a testicle-sack in the form of a flat strip; and shirring means forming an 100 operative connection between the supporting means and the ends of the strip to hold the latter in sack-like form.

2. A suspensory combining with a supporting means, a testicle-sack in the form of a flat strip having its ends outwardly convexed; and shirring-means engaged with the supporting means and with the outwardly convexed portions of the strip to hold the latter in sack-like form. 105

3. A suspensory embodying a support; a testicle-sack in the form of a flat strip having guides at its ends; and loop-shaped members connected with the support and threaded through the guides to hold the strip in sack-like form.
4. A suspensory embodying a support; a testicle-sack in the form of a flat strip having oppositely convexed guides at its ends; and loop-shaped members connected with the support and threaded through the oppositely convexed guides to hold the strip in sack-like form.
5. A suspensory embodying a support; a testicle-sack in the form of a flat strip having guides at its ends; and loop-shaped members connected with the support and threaded through the guides to hold the strip in sack-like form; the loop-shaped members being

secured to the guides intermediate the ends 20 of the respective guides.

6. A suspensory embodying a support; a testicle-sack in the form of a flat strip having oppositely convexed guides at its ends; and loop-shaped members connected with the 25 support and threaded through the oppositely convexed guides to hold the strip in sack-like form, the loop-shaped members being secured to the strip intermediate the ends of the respective guides.

In testimony that I claim the foregoing as my own, I have hereto affixed my signature in the presence of two witnesses.

HARRY J. MARTIN.
